ELECTRICAL SWITCH WITH HOUSING HAVING INTERNAL GROUND CONTACT

Filed Feb. 21, 1966

FIG. 1

1

3,316,364

ELECTRICAL SWITCH WITH HOUSING HAVING
INTERNAL GROUND CONTACTWilliam N. Schink, Crystal Lake, Ill., assignor to Indak
Manufacturing Corp., Northbrook, Ill., a corporation
of IllinoisFiled Feb. 21, 1966, Ser. No. 529,051
10 Claims. (Cl. 200—16)

This invention relates to electrical switches.

One object of the present invention is to provide an electrical switch in which at least one contact is grounded to the casing of the switch in a new and improved manner.

A further object is to provide such a new and improved switch in which the grounded contact is mounted on or formed integrally with a portion of the casing.

It is a further object to provide such a new and improved switch in which the grounded contact is mounted on or formed integrally with a tab or lug projecting inwardly from one wall of the casing, adjacent the other contacts of the switch and in front of the insulating support for the other contacts.

Another object is to provide a new and improved switch of the foregoing character in which the grounded contact may take the form of a contact rivet or the like, mounted on such tab, or a contact point or boss formed integrally with such tab.

A further object is to provide such a new and improved switch in which the grounding of one or more contacts is accomplished at extremely low cost and in such a manner that the switch is easy to manufacture and reliable in operation.

Further objects and advantages of the present invention will appear from the following description, taken with the accompanying drawings, in which:

FIG. 1 is a fragmentary side elevational view of an electrical switch to be described as an illustrative embodiment of the present invention.

FIG. 2 is a fragmentary rear elevational view of the switch.

FIG. 3 is a rear view of the switch with the contact supporting plate removed, the view being taken generally as indicated by the line 3—3 in FIG. 1.

FIG. 4 is an elevational view of the front or inner side of the contact supporting plate, the view being taken generally as indicated by the line 4—4 in FIG. 1.

FIG. 5 is an enlarged cross section, taken generally along the line 5—5 in FIG. 2.

FIG. 6 is a fragmentary cross section similar to a portion of FIG. 5 but showing the manner in which the casing tab is bent inwardly after the grounded contact rivet has been mounted thereon.

FIG. 7 is a fragmentary cross section similar to FIG. 6 but showing a modified construction in which the contact rivet is replaced with a contact point or boss formed integrally with the casing tab.

FIG. 8 is a fragmentary elevational view, taken generally as indicated by the line 8—8 in FIG. 7.

FIG. 9 is a view similar to FIG. 4 but showing a switch utilizing the modified grounded contact of FIGS. 7 and 8.

As already indicated, FIG. 1 illustrates an electrical switch 10 which is especially well adapted for automotive service, for use on automobiles, trucks or the like, but will also find many other applications. The illustrated switch 10 comprises an electrically conductive casing 12 which preferably is made of metal. As shown, the casing 12 is formed from sheet metal into a rectangular shape, but the present invention is applicable to casings of various shapes and constructions.

A contactor 14 is movably mounted within the casing

2

12, preferably on a movable carriage 16. As shown, the carriage 16 is slideable longitudinally along the inside of the casing 12. The illustrated casing 12 has a front wall 18 and a pair of longitudinal side walls 20 and 22 which serve as guides for the carriage 16. The casing 12 has a pair of end walls 24 and 26 which retain the carriage within the casing.

Various means may be provided for operating the carriage 16. For example, the illustrated switch is provided with an operating lever 28 which is swingable about a pivot 30, mounted on a bracket 32 projecting forwardly from the casing 12. The lever 28 has an arm 34 which projects rearwardly into the casing 12 and is received in an opening 36 formed in the carriage 16. An appropriate slot or opening is formed in the front wall 18 of the casing 12 to receive the arm 34.

The contactor 14 is movable into engagement with a plurality of contacts or points. Four such contact points 41—44 are provided in the illustrated construction. At least one of the contact points is grounded directly to the casing 12. In the illustrated construction, the contact 41 is thus grounded, in a manner to be described in detail presently.

The other contacts 42—44 are mounted on a supporting member 46 made of insulating material. The member 46 preferably takes the form of an insulating board or plate which is secured to the casing 12 so as to form the rear wall thereof.

A plurality of tabs 48 or other fastening elements are formed on the casing 12 to retain the insulating plate 46. The illustrated tabs 48 extend through slots or notches 50 which are formed in the edge portions of the insulating plate 46. The tabs 48 are bent or clinched inwardly, behind the insulating plate 46, so that the plate will be securely fastened to the casing.

The contacts 42—44 preferably take the form of rivets which extend through suitable openings 51 in the insulating plate 46. Suitable terminals 52—54 may be secured to the rear ends of the rivets 42—44 and against the rear or outer side of the insulating plate 46.

Suitable spring means are provided to press the contactor 14 rearwardly against the contacts 41—44 and also against the insulating plate 46. Thus, one or more springs may be provided between the contactor 14 and the carriage 16. In the illustrated construction, a coil spring 56 is compressed between the contactor 14 and the carriage 16.

The illustrated contactor 14 is retained and guided on the carriage 16 by means of guide tabs or lugs 58 which project from the contactor toward the front of the switch. The tabs 58 are slidably retained in notches or slots 60 which are formed in the carriage 16.

In addition to biasing the contactor 14 rearwardly against the contacts 41—44, the spring 56 biases the carriage 16 against the front wall 18 of the casing 12. It is preferred to provide detent elements on the front wall 18, and also on the carriage 16, to locate and detain the carriage in its various operating positions. The detent elements on the illustrated carriage take the form of ridges or lugs 62 which project forwardly therefrom. As to the front wall 18, the detent elements take the form of alternate ridges 64 and grooves 66, adapted to receive the ridges 62. When the carriage 16 is moved along the inside of the casing, the detent projections 62 ride over the ridges 64 and into the grooves 66. Due to the biasing action of the spring 56, the detent projections 62 are detained in the grooves 66.

As already indicated, the grounded contact 41 is mounted or formed on a portion of the casing 12. Thus, the contact 41 is grounded through the casing. When mounted in an automobile or the like, the casing is normally connected to the body of the automobile. Thus, the

casing becomes a part of the grounded side of the electrical system.

In the construction shown in FIGS. 1-6, the contact 41 takes the form of a contact rivet which is secured to a tab or flange 68 extending inwardly from one wall 20 of the casing 12. An opening or hole 70 is formed in the tab 68 to receive the contact rivet 41. It will be seen that the tab 68 is folded or bent inwardly from the casing, so as to extend adjacent the front or inner side of the insulating plate 46. It is preferred to arrange the tab 68 so that the front or inner side of the insulating plate 46 firmly engages the rear side of the tab 68, so that the contact rivet 41 will be in the same plane as the other contact rivets 42-44. The heads of the contact rivets 42-44 are made thicker than the head of the rivet 41, so as to allow for the thickness of the tab 68.

In the construction of FIGS. 1-6, it is preferred to form an opening or hole 72 in the insulating plate 46, to receive the upset rear end 74 of the grounded contact rivet 41. The opening 72 is made large enough to provide clearance around the upset portion 74.

In the manufacture of the switch, it is preferred to secure the contact rivet 41 to the tab 68 before the tab is bent or folded inwardly from the side wall 20 of the casing 12. In FIG. 6, the original position of the tab 68 is shown in full lines, while the inwardly folded position is shown in broken lines. In its original position, the tab 68 projects rearwardly from the side wall 20 of the casing. A score mark or groove 76 is preferably formed between the side wall 20 and the tab 68 to insure that the tab will be folded inwardly along the correct junction line. The tab 68 is folded inwardly before the insulating plate 46 is secured to the rear side of the casing 12. To insure firm engagement between the insulating plate 46 and the tab 68, the tab may be folded inwardly at an angle slightly less than 90 degrees, so that the tab will be folded inwardly by an additional amount when the insulating plate is pressed against and secured to the rear side of the casing 12. Thus, the insulating plate itself completes the inward folding movement of the tab 68.

The switch 10 may employ various arrangements of the contacts 41-44. In the illustrated arrangement, the contacts 42 and 43 are in one row, while the contacts 41 and 44 are in a parallel row. The contacts 42 and 43 are staggered upwardly relative to the contacts 41 and 44.

When the contactor 14 is in its uppermost position, as shown in FIG. 2, the contactor engages only the contact 42. This constitutes the Off position of the switch. The contactor 14 may be moved downwardly to its first operating position, in which the contactor engages the grounded contact 41, in addition to the contact 42. An insulating point or boss 78 may be provided on the insulating plate 46 to engage the contactor 14, so as to provide three points of contact with the contactor. The insulating boss 78 is preferably in the form of a semi-perforation, extruded or stamped forwardly from the insulating plate 46.

Further downward movement of the contactor 14 brings it to its next operating position, in which the contactor engages the contacts 41, 42 and 43. When the contactor is moved downwardly to its lowermost position, it engages the contacts 41, 43 and 44.

The switch may be employed in a variety of circuits to carry out various control functions. Such a circuit is shown by way of example in FIG. 2. The illustrated circuit is adapted to control the speed of a motor 80 for a blower or other device. The motor 80 is connected between the contact 44 and the ungrounded side of the battery 82. Of course, the other side of the battery is grounded, and thus is connected to the contact 41, which is grounded through the casing 12. A resistor 84 is connected between the contacts 43 and 44. Another resistor 86 is connected between the contacts 42 and 43.

When the contactor 14 is in its uppermost position, the

motor 80 is off, because the energizing circuit to the grounded contact 41 is open. When the contactor 14 is moved downwardly so as to engage the grounded contact 41, the energizing circuit for the motor 80 is completed through the resistors 84 and 86, so that the motor operates at low speed. In its next position, the contactor engages the contact 43 so as to short-circuit the resistor 86. Thus, the motor is energized through the resistor 84, so that the motor operates at medium speed.

In the final or lowermost position of the contactor 14, it forms a circuit between the grounded contact 41 and the contact 44, so that the motor 80 is energized directly from the battery 82. Both of the resistors 84 and 86 are ineffective. Thus, the motor operates at maximum or high speed.

The contacts 41-44 are preferably made of copper or some other highly conductive material. The use of such a material insures the maintenance of low contact resistance between the contacts and the contactor 14, which also is normally made of copper or some other highly conductive material. Very little cost is involved in forming the grounded contact 41 as a separate contact rivet or other member, mounted on the tab 68.

However, even this small element of cost may be eliminated in some cases by forming a contact point or boss 141 integrally with the tab or flange 68, as shown in FIGS. 7-9. As in the case of the contacts 41-44, the integral contact 141 is made with a generally spherical curvature. The casing 12 is normally made of sheet steel, with a zinc or cadmium plating thereon. The plated steel is not as good as a contact material as the copper of the rivet 41, but is good enough to meet the requirements of many situations. Thus, the integrally formed steel contact 141 will give reliable service and adequately long life, provided the conditions of service are not too severe.

When the integrally formed steel contact 141 is employed, it is preferred to arrange the switch so that the contactor 14 always engages the grounded contact 141, in all positions of the switch. FIG. 9 illustrates such a modified contact arrangement, in which the contactor 14 always engages the contact 141, and is movable into engagement with a series of contacts 142-144, mounted on the insulating plate 46. The other contact points 142-144 are preferably made of copper or some other highly conductive material. The tab or flange 68 is bent or folded inwardly from the casing in the same manner as in the case of the switch of FIGS. 1-6.

It will be understood that the present invention provides a switch having at least one contact grounded directly to the casing of the switch. In this way, there is no need to provide any wire or other external connection to the grounded contact. The cost of the wire is thus avoided. The grounded contact is preferably mounted or formed directly on a tab or flange projecting inwardly from one wall of the casing. Thus, the grounded contact may be provided at very low cost. Moreover, the electrical resistance between the contact and the grounded casing is very low. The grounded contact is in the same plane as the other contacts and is rigidly supported against the insulating member which supports the other contacts.

The present invention provides a switch which is extremely low in cost yet will remain reliable in operation over an extremely long service life.

Various other modifications, alternative constructions and equivalents may be employed without departing from the true spirit and scope of the invention, as exemplified in the foregoing description and defined in the following claims.

I claim:

1. In an electrical switch, the combination comprising a casing made of conductive material, a contactor movable in said casing, means for moving said contactor within said casing, said means comprising an insulating carriage supporting

said contactor and confined within said casing for movement along a predetermined path therein, an insulating member on said casing opposite said contactor, at least one contact mounted on said insulating member and engageable by said contactor, a conductive member formed integrally with said casing and adjacent the inner side of said insulating member within said casing, and at least one contact on said conductive member and engageable by said contactor for connecting said contactor to ground through said casing.

2. A combination according to claim 1, in which said casing is made of sheet metal, and said member on said casing comprises a flange bent inwardly from one wall of said casing.

3. A combination according to claim 1, in which said last mentioned contact comprises a contact rivet mounted on said member on said casing.

4. A combination according to claim 1, in which said last mentioned contact comprises a contact point formed integrally with said member on said casing.

5. A combination according to claim 3, in which said insulating member is formed with an opening for receiving said contact rivet.

6. In an electrical switch, the combination comprising a metal casing, a carriage movable in said casing, means for moving said carriage within said casing, a contactor mounted on said carriage and movable therewith,

5

10

20

30

an insulating member mounted on said casing opposite said contactor and forming one wall of said casing, at least a first contact mounted on said insulating member and engageable by said contactor, at least one tab formed integrally with one wall of said casing and projecting into said casing adjacent the inner side of said insulating member, and at least a second contact on said tab and engageable by said contactor for connecting said contactor to ground through said casing.

7. A combination according to claim 6, in which said second contact comprises a highly conductive contact point mounted on said tab.

8. A combination according to claim 6, in which said second contact comprises a conductive contact rivet mounted on said tab.

9. A combination according to claim 8, in which said insulating member is formed with an opening for receiving said contact rivet.

10. A combination according to claim 6, in which said second contact is in the form of a contact point formed integrally with said tab.
